UNITED STATES PATENT OFFICE.

GEORGE ADSIT, OF PATERSON, NEW JERSEY, ASSIGNOR TO BENJAMIN EASTWOOD COMPANY, OF PATERSON, NEW JERSEY, A CORPORATION OF NEW JERSEY.

QUILLING-MACHINE.

1,178,045.

Specification of Letters Patent.

Patented Apr. 4, 1916.

Application filed October 21, 1914. Serial No. 867,777.

To all whom it may concern:

Be it known that I, GEORGE ADSIT, a citizen of the United States, residing at Pater-
son, in the county of Passaic and State of
5 New Jersey, have invented certain new and
useful Improvements in Quilling-Machines,
of which the following is a specification.

In a certain class of winding machines
there is arranged beside the spindle or the
10 like means on which to wind the package a
thread-guiding means which includes a ro-
tary threaded member and a nut engaged
with the threading of said member. To
form the package either the thread-guiding
15 means or the spindle (compare my Patents
Nos. 757,081 and 919,298) is reciprocated
lengthwise of the axis of winding so as to
place successive layers of the windings
around said axis, and the necessary progress
20 of the thread-guiding point to build the
package longitudinally is obtained by con-
tact from time to time in the growth of the
package of the threaded member (specifi-
cally, a friction wheel forming a part there-
25 of) with the revolving package, which im-
parts a rotary impulse to the threaded mem-
ber and so feeds it along in the nut. In
forming a wound package in such machines
on a paper tube or the like core or holder
30 lacking an enlargement at the butt against
which said member can impinge at the out-
set of the operation of forming the pack-
age, it has been proposed to provide for
lateral movability, one with reference to the
35 other, of the spindle or said member and
thereby derive from the rotating spindle the
rotary impulses which result in the progres-
sion of the threaded member, thereby to ef-
fect the placement of the first layers in
40 stepped formation until such a nucleus of
the windings (which will form in the com-
pleted package its butt or heel) has been
produced that thereafter the progress of the
threaded member can follow as the result
45 of the impact between the said member and
the package incident to the normal or longi-
tudinal thrust of whichever of said devices
reciprocates.

The object of this invention is to provide
50 a mechanism of the kind indicated with a
simple, reliable and efficient means whereby
the said shifting may take place in a way
calculated to insure not only uniformity of
winding as to the butt portions of a run of
55 the packages but such a placement of the

layers or coils thereof as will avoid the
catching or snarling of the threads when
drawn from the packages.

In the accompanying drawings, wherein
the invention is illustrated in connection
with both of the mentioned types of a ma-
chine of the class indicated, Figure 1 is a
plan, partly in section, and Fig. 2 a front
elevation, of a mechanism of the type of
that illustrated in my Patent No. 757,081; 60
Fig. 3 is a plan view, partly in section, of a
mechanism of the type of that illustrated
in my Patent No. 919,298; Fig. 4 is a side
elevation of the novel means I employ to
attain the objects stated and of the spindle 70
and thread-guiding means; Figs. 5, 6 and 7
are views of details of my improvement;
and, Fig. 8 is a diagrammatic view illus-
trating the building of the heel or butt of a
75 package.

In Figs. 1 and 2, *a* is the spindle and *b*
the thread-guiding means, the latter com-
prising with the rotary threaded rod *c*
equipped with a friction wheel *d*, the thread-
guide rod *e*, means *f* to couple the two rods 80
for movement together lengthwise of the
winding axis, and a nut *g* engaging the
threading of rod *c* and in the present case
being the upper end of a fork *h* upstanding
from the rock-shaft *i*. Here, the spindle *a*
being rotated by the rotary driving medium
j with which it is clutched, and shaft *i* be-
ing rocked, as the result of the reciproca-
tion of the thread-guiding means layers of
coils of the thread are wound on the spindle 90
(that is, on the paper tube *A* placed there-
on), and from time to time in the backward
thrusts of the thread-guiding means the rod
c is given a rotary impulse by contact of
its wheel *d* with the part of the package 95
already formed, the rod thus progressing
forward in the nut *g* to successively advance
the layers.

In Fig. 3, *l* is the spindle and *m* the
thread-guiding means, the latter comprising
with the rotary threaded rod *n* equipped
with a friction wheel *o*, the thread-guide rod
p, means *q* to couple the two rods for move-
ment together lengthwise of the winding
axis, and a nut *r* engaging the threading of
rod *n* and in the present case fixed to some
part of the frame *B* of the machine. Here,
the spindle being rotated by the driving
medium *s* with which it is clutched, and be-
ing also reciprocated relatively to the 110

thread-guiding means by the means t on the one hand engaging between two collars u on the spindle and on the other hand pivoted to the post u' upstanding from rock-shaft u'' , 5 layers of coils of thread are wound on the spindle (that is, on the paper tube A placed thereon) substantially the same as in the construction shown in Figs. 1 and 2, and from time to time in the forward thrusts of 10 the spindle the rod n is given a rotary impulse by contact of its wheel o with the part of the package already formed, the rod thus progressing forward in the nut r to successively advance the layers.

15 Reference may be had, if necessary, to the two patents already named for further explanation of these mechanisms, whose essential features are stated above. For adapting these mechanisms to the winding of a 20 package on a paper tube or the like lacking an enlargement against which the wheel d (or o) may impinge to effect at the outset the advance of the layers of windings lengthwise of the axis of winding I provide 25 the instrumentalities shown in Figs. 4 to 7, described as follows: The front rail of the frame B has a horizontal slot v in which the body part or rod c (or n) of the thread-guiding device is capable of lateral shifting 30 movement. To said rail is affixed a bracket w having a transverse cylindrical portion or guideway x pierced by a horizontal slot y registering with the slot v , and also having a downwardly projecting arm z formed with 35 a bearing 2 whose axis is oblique to the axis of winding, being a pin held in the arm by the set-screw 3. On this bearing is fulcrumed the bifurcated lower end of a shifter lever of shifter 4, the upper end of which is 40 forked and rounded at the front, receiving snugly therein the rod c (or n) and being adapted to bear against a collar 5 adjustably fixed on said rod. The shifter is normally 45 pressed outwardly by the spring 6 (Fig. 4), one end of which is engaged with the arm z and the other with the shifter. To preserve 50 the rod c (or n) in a definite horizontal plane at its forward end-portion it is journaled in a sliding plug 7 fitting the guideway x . An adjusting screw 8 tapped into 55 the arm determines the outward limit of movement of the shifter, which it will be noted involves displacement of its free or forked end laterally of the spindle axis, due to the fulcrum being oblique to said axis. The instrumentalities shown in Figs. 4 to 7 are assembled with the two types of mechanism illustrated in Fig. 1 and Figs. 2 and 3 in identically the same way.

60 Operation: Referring, first, to Figs. 1 and 2. The thread guiding means being set full back (so that the nut q is engaged with the threading of rod c at the forward limit) and the spindle being rotated and shaft i rocked, 65 shifter 4 will be oscillated back and forth,

being pressed back by the collar 5 and forward by its spring 6. The result of its backward and forward movement is the shifting toward and from the winding axis of its free or forked end, and consequently 70 of rod c , because the fulcrum of said shifter is oblique to the axis of winding. Hence, wheel d will from time to time be brought against the windings on the tube A, and each such impact resulting in rotation of the 75 rod d in nut g the winding point, while traversing, will gradually progress forward, so that the layers of windings become disposed as graphically shown by Fig. 8. The movements of the rod d toward the spindle grow 80 less and less in extent because the impulses which the shifter derives from the collar 5 grow shorter in extent as the rod c progresses forward, until the shifter finally ceases to be actuated by the collar 5 altogether, whereupon further building of the 85 package proceeds in the regular way, *i. e.*, by virtue of the impacts of wheel d with the package incident simply to the thrusts lengthwise of the winding axis. 90

Referring to Fig. 3: The thread guide means being set full back and there held by the nut r and holding the shifter full back (as in the dotted line position, Fig. 4) and the spindle rotated and reciprocated, wheel o 95 will impinge against the windings on tube A from time to time, each such impact resulting in rotation of rod n in nut r and the consequent forward progress of said rod and the winding point, and also the shifting of 100 said rod laterally away from the winding axis, due to the controlling influence of the shifter which is confined to swing on an axis oblique to the axis of winding, so that the layers of windings become disposed as 105 represented in Fig. 8. When the collar 5 finally clears the shifter the building of the package proceeds in the regular way, *i. e.*, by virtue of the impacts of the package with wheel o incident to the thrusts lengthwise of 110 the winding axis.

When the summit C of the butt windings has been reached, the shifter should become further ineffective to influence the rod c (or n); wherefore the screw 8 is provided for 115 adjustably determining the forward limit of movement of the shifter.

It will be understood that by changing the degree of obliquity of the fulcrum of the shifter to the winding axis, the taper of the butt or heel may be pitched as desired.

Having thus fully described my invention, what I claim as new and desire to secure by Letters Patent is:

1. In combination, with the frame, a rotary means on which to wind the package, a thread guiding means including a rotary threaded member having contact with and thereby rotated by the rotating package and 130

- a nut engaged with the threading of said member, means to reciprocate one of the first-named means, and means to effect a relatively lateral movement as between the first-named means and said member including a shifter engaged with one of them and pivoted on an axis oblique to the winding axis.
2. In combination, with the frame, a rotary means on which to wind the package, a thread guiding means including a rotary threaded member having contact with and thereby rotated by the rotating package and a nut engaged with the threading of said member, means to reciprocate one of the first-named means, and means to effect a relatively lateral movement as between the first-named means and said member including a spring-pressed shifter engaged with one of them and pivoted on an axis oblique to the winding axis.
3. In combination, with the frame, a rotary means on which to wind the package, a thread guiding means including a rotary threaded member having contact with and thereby rotated by the rotating package and a nut engaged with the threading of said member, means to reciprocate one of the first-named means, and means to effect a relatively lateral movement as between the first-named means and said member including a shifter engaged with said member and pivoted on an axis oblique to the winding axis.
4. In combination, with the frame, a rotary means on which to wind the package, a thread guiding means including a rotary threaded member having contact with and thereby rotated by the rotating package and a nut engaged with the threading of said member, means to reciprocate one of the first-named means, and means to effect a relatively lateral movement as between the first-named means and said member including a spring-pressed shifter engaged with one of them and pivoted on an axis oblique to the winding axis.
5. In combination, a spindle, a thread guiding mechanism, means to reciprocate one of them lengthwise of the winding axis, said mechanism having coactive screw-and-nut instrumentalities to advance said mechanism lengthwise of the winding axis and having one of the coactive parts of said mechanism adapted to contact with and to be rotated by the rotating package, means to support the spindle, the thread guiding mechanism and the first-named means, and means to effect a relatively lateral movement as between the spindle and thread-guiding mechanism including a shifter engaged with one of them and pivoted on an axis oblique to the winding axis.

In testimony whereof I affix my signature in presence of two witnesses.

GEORGE ADSIT.
